UNITED STATES PATENT OFFICE.

CAMILLO KROMER, OF ALBANY, NEW YORK.

VELOCIPED OR BICYCLE.

SPECIFICATION forming part of Letters Patent No. 498,800, dated June 6, 1893.

Application filed October 19, 1892. Serial No. 449,387. (No model.)

To all whom it may concern.

Be it known that I, CAMILLO KROMER, of Albany, in the county of Albany and State of New York, have invented a new and useful Improvement in Velocipedes or Bicycles, which is fully set forth in the following specification.

This invention has reference to velocipedes or bicycles and particularly to that class in which the driving wheel is operated by an oscillating pedal.

The object of the present invention is the provision of a clutch mechanism which can be thrown into and out of engagement with the drive-wheel at the will of the rider, thereby releasing the pedals which may be moved to throw a suitable brake into operation. This feature of the invention together with other important details of construction may be fully understood by reference to the accompanying drawings, in which—

Figure I, is a side elevation of my improved machine. Fig. II, is a front view of the steering wheel. Fig. III, is a vertical section, taken 25 from the rear, on line III of Fig. I. Fig. IV, is an enlarged side elevation of the rack-frame. Fig. V, is a detail view of the pedal. Figs. VI, VII and VIII are details of a modification of the rack-bar and pedal therefor, 30 and Fig. IX, is a perspective view of the spring seat support.

In the drawings A represents the drive or rear wheel, B the front or steering wheel, C the handle bar and D the seat. On each side 35 of the drive wheel are two parallel bars *a* between which are clamped the ends of the curved guard *a'* which passes around the upper portion of the wheel. A U-shaped brace *a''* is secured at about its middle to the curved 40 guard *a'* and extends down on opposite sides of the wheel A, where it is firmly secured to the parallel bars *a*. In the brace *a'* just below the upper of parallel bars *a* are formed 45 bearings for the ends of shaft *a''* of the drive-wheel. This shaft projects beyond the brace *a''* and carries at its outer ends drive pinions D' formed at their inner and outer edges with circular flanges *d*.

Pivoted to the extreme lower ends of the 50 brace *a''* are oscillatory rack-frames, each consisting of a forwardly extending bar *e* curved outwardly and upwardly at its forward end

and formed with a slot *e'* therein, a rearwardly extending arm *e''*, carrying a brake-shoe *e'''* which is adapted to be thrown into contact 55 with flanges *d* of drive pinion D', and the S-shaped rack-bar F, the lower end of which passes through a slot in the end of arm *e''* and which is provided with a lug *f* held in engagement with said arm *e''* by a spring *f'*. The 60 forward portion of said rack-bar passes through a slot in a guide-arm *e''* and its end engages under the inner end of a pivoted 65 pedal block *f''*. Said pedal block is pivoted at about its middle to the inwardly extending arm *f'''* of bar *e*, which is provided at its inner end with an upward right angle extension, formed with a slot *f''* therein. The pedal block has projecting pins *f''''* at its ends which 70 slidingly engage in slots *e'* and *f''*. The end of the rack-bar engaging under the pedal block is normally held up and out of engagement with the pinion D by a spring *f''''* which 75 also serves to hold up the inner end of the pedal-block. Springs *f''''* connected at one end with the brace *a''* and at the other end with the rack-frame serve to normally hold the latter at the limit of its upward movement and return the same to that position at the end of each stroke. Instead of the springs I 80 may use a cord *x* (shown in Fig. I) connected to the rack-frames on the opposite sides of the machine and engaging over a pulley *y* secured to the guard *a'*.

The back-bone of my machine is preferably 85 formed of the two curved pieces of wood *g*, secured at their lower ends between the bars *a*, curved forwardly and upwardly, carrying at their upper ends a bearing for the head or steering rod *H* of the machine to which is secured the handle bar C.

h represent flat springs, two on each side of the front wheel, having right angle extensions at their upper ends which are adapted to be clamped between blocks *h'* secured to 95 the lower end of the head or steering rod *H*, the lower ends thereof being curved outwardly in opposite directions parallel with the plane of the front wheel. Adjustably secured to the axle or shaft *a''* of the wheel B 100 by clamps *c* are curved springs *c'* secured at their extremities to the ends of the curved lower portions of springs *h*. This construction allows the adjustment of the front-wheel

along the springs c' thereby compensating for unevenness in the tension of the springs. Instead of having the two springs h on each side of the wheel I may form both springs 5 continuous by joining the right angle extensions, which is probably the preferable construction for strength.

The seat support is formed of a double spring k and the single spring k' which passes 10 between the upper portion of the double spring. The upper ends of both springs are pivotally secured to the ends of seat-spring k^2 to which the seat D is adjustably clamped.

Instead of the S-shaped rack-bars F and the 15 pinion D, I may employ the strap m (of leather or other suitable material) as shown in Figs. VI and VII, adapted to encircle a drum M, said strap being divided into two parts at one end, and secured to the arm e^2 passing up, over and 20 around the drum M, the opposite or single end of the strap passing forward between the divided end thereof and under the inner end of pedal block f^2 , and is secured to the forwardly extending bracket m' on arm f^3 . 25 This strap normally engages loosely about drum M, but upon the rider pressing down upon the inner end of pedal block f^2 , the strap is made taut and grips the drum.

In operation the rider upon the downward 30 movement of the pedal exerts the pressure of his foot on the inner end of block f^2 , thereby throwing the gearing into operation and revolving the drive-wheel. When the end of the stroke is reached he shifts the pressure of 35 his foot to the outside of the block, thereby disengaging the gear and allowing the spring f^6 to return the rack-frame to its normal position. If it is at any time desired to put on the brake it is only necessary to throw the 40 driving gear out of engagement and force the rack-frame downward until the brake-shoe e^3 comes into contact with the circular flanges d . By this construction great power can be applied to the brake—without danger of 45 "looping" or otherwise injuring the tire.

I do not wish to limit myself to the exact forms of clutch mechanisms shown, as it is obvious that other modifications may be substituted with the same result.

50 Having fully described my invention, what I claim as new, and desire to secure by Letters Patent, is—

1. In a velocipede, the combination with the drive-wheel, of a pivoted driving frame, carrying gearing for connecting said frame with the drive wheel, a pedal-block secured to and movable with reference to said driving frame, and means whereby upon the movement of the pedal-block the gearing may be thrown 55 into or out of engagement, substantially as described.

2. In a velocipede the combination with the drive-wheel, and an oscillating driving frame, of a rack-bar carried by said frame and adapted 60 to engage a pinion on the axle of the drive-wheel, and a pivoted pedal-block on the for-

ward end of the driving frame connected with said rack-bar, whereby the latter is thrown into and out of engagement with the pinion upon the movement of said pedal-block on its 70 pivot, substantially as described.

3. In a bicycle or velocipede, the combination with the drive-wheel, main frame, and pinion on the axle of the drive-wheel, of a forwardly extending rack-bar above said pinion, carried by the driving frame, a pivoted 75 pedal-block on the forward end of the driving frame, under one end of which the rack-bar engages and means for normally holding the rack-bar out of engagement with the pinion on the drive-shaft, substantially as described.

4. In a velocipede the combination with the drive-wheel of a pivoted driving frame carrying the pedal, driving mechanism for connecting said frame with the drive-wheel, means for throwing said driving mechanism into and out of engagement with a pinion of the shaft of the drive-wheel, a flange around the edge of said pinion, and a brake-shoe on 85 the driving frame adapted to be brought into contact with said flange, substantially as described.

5. The combination with the steering wheel of a fork comprising substantially parallel 95 springs extending down on opposite sides of said wheel, and curved outwardly in opposite directions at their lower ends, downwardly curved connecting springs fixed at their ends to the ends of the downwardly extending 100 springs, and connections between said connecting springs and the steering wheel, substantially as described.

6. The combination with the steering wheel of a fork comprising substantially parallel 105 springs extending down on opposite sides of said wheel, and curved outwardly in opposite directions at their lower ends, downwardly curved connecting springs fixed at their ends to the ends of the downwardly extending 110 springs, and bearings for the steering wheel adjustable along said connecting springs, substantially as described.

7. The combination with the frame work and seat, of a seat support consisting of an 115 upwardly extending double spring, a spring passing up between the upper portion of said double spring, both of said springs being secured at their lower ends to the frame of the machine, and a seat spring to which the seat 120 is clamped, and to the ends of which are pivotally connected the upper ends of the upwardly extending springs, substantially as described.

In testimony whereof I have signed this 125 specification in the presence of two subscribing witnesses.

CAMILLO KROMER.
